UNITED STATES PATENT OFFICE.

JOHN G. WILSON, OF CHICAGO, ILLINOIS.

MECHANICALLY-OPERATED FIGURE TOY.

Application filed May 28, 1925. Serial No. 33,498.

To all whom it may concern:

Be it known that I, JOHN G. WILSON, a citizen of the United States, residing at Chicago, in the county of Cook and State 5 of Illinois, have invented certain new and useful Improvements in Mechanically-Operated Figure Toys; and I do declare the following to be a full, clear, and exact description of the invention, such as will enable 10 others skilled in the art to which it appertains to make and use the same.

My invention relates to improvements in toys of the type having movably mounted figures which are manipulated to simulate 15 the actions of living creatures, and the object of the present invention is to provide an extremely simple and inexpensive toy of this character, yet one which will produce a great deal of amusement.

20 A further object is to provide a toy which will simulate two roosters fighting, the construction being such that their movements are imitated in an effective manner.

With the foregoing in view, the invention 25 resides in the novel subject matter herein-after described and claimed, the description being supplemented by the accompanying drawings.

Figure 1 is a front elevation showing 30 the normal positions of the two figures of the toy.

Figure 2 is a central vertical longitudinal section.

Figure 3 is a horizontal sectional view on 35 line 3—3 of Fig. 2.

Figure 4 is an end elevation.

Figure 5 is a vertical transverse sectional view on line 5—5 of Fig. 1.

Figure 6 is a view similar to Fig. 1, but 40 illustrating the manner in which the two figures tilt away from each other when they are lowered into contact with the base of the toy.

Figure 7 is a vertical transverse sectional view as indicated by line 7—7 of Fig. 6.

The form of construction selected for illustration in the present application, will be hereinafter rather specifically described, with the understanding however, that within 50 the scope of the invention as claimed, numerous modifications may be made.

The numeral 1 designates an elongated casing which is provided with a base 2, a roof 3, and a transparent front panel 4, said casing being preferably made to simulate 55 a small chicken house. Behind the

panel 4 and in parallel relation therewith, is a second panel 5 which may be formed of any desired material, but is preferably of compressed fibre, on account of the inherent stiffness thereof. The two panels 4 and 5 are held in appropriate spaced relation by vertical cleats 6 secured to the inner sides of the casing ends, and to prevent upward movement of said panels, as well as to 60 close the space between their upper edges, I prefer to make use of a horizontal strip 7 whose ends may be nailed to certain of the strips 6.

Behind and substantially parallel with 70 the panel 5 is a resilient plate 8 whose lower end is anchored to the casing in any preferred manner. In the construction shown, it is secured by nails 9 to a horizontal strip 10, the latter being in turn 75 secured to the base 2, by nails 11. Two slidably supported cords 12 are connected to the upper end of the plate 8, and these cords are preferably passed through openings 13 in the upper edge portion of the 80 panel 5. Figures 14 are hung upon the lower ends of the cords 12 and are located in the space between the panels 4 and 5, and means is provided for alternately springing the plate 8 toward the panel 5 and releasing 85 said plate, so that the figures 14 will first be moved downwardly and will then be quickly jerked upwardly. These figures preferably represent two roosters and when they are free of the base 2, they are in 90 balanced positions, as shown in Fig. 1.

They are, however, provided with feet 15 which are adapted to contact with the base 2 when the figures are lowered, and these legs are so positioned as to cause the figures 95 14 to tilt rearwardly upon them, as said figures reach their extreme lowered positions. As illustrated, the feet 15 are positioned forwardly of the center of gravity and have their bottom portions upwardly 100 and rearwardly inclined to effect normal setting of the figures as shown in full lines in Figure 6. Thus, an effective simulation is given, of two roosters preparing to jump toward each other, when fighting, and as 105 soon as the cords 12 are jerked upwardly, not only are the figures 14 upwardly moved as shown in dotted lines in Fig. 6, but the initial movement of these figures is a forward tilting, giving the appearance that the 110 roosters are jumping toward each other and pecking with their bills. Moreover, as the

figures are jerked into the air from the base 2, a rooster fight is still further simulated, giving the appearance that they are attempting to use their spurs.

5 While any desired means may be employed for actuating the resilient plate or spring 8, I prefer to make use of a longitudinal crank shaft 16, for this purpose. One end of this shaft passes through one 10 end of the casing 1, in the present disclosure, and is provided with an operating handle 17, while the other end of said shaft is rotatably mounted in an opening in the bearing plate 18, said bearing plate being 15 secured to cleats 19 within the casing. In the form of construction shown, the crank 17 is of course intended to be turned by hand, so that the shaft 16 is caused to alternately force the plate 8 forwardly and 20 release it. In this connection, it may be stated that Fig. 5 shows the normal position of the plate 8, whereas Fig. 7 discloses it sprung forwardly by the crank shaft 16 and discloses the latter in readiness to release said plate, so that it may jerk upon the cords 12 to rapidly raise the figures 14 and at the same time tilt them forwardly as above set forth.

30 The form of construction shown may well be used when the device is to be operated by hand. If desired, however, the shaft 16 could be connected with an electric motor, a spring motor, a wind-wheel, or any other desired means whereby it could be rotated.

35 I claim:

1. A toy comprising a vertical panel, a plurality of figures in front of said panel, a plurality of cords on which said figures are hung, said cords being slidably supported upon said panel, a spring mounted behind and having a portion movable toward and from said panel, said cords being connected to said spring portion, and means for alternately forcing said spring portion toward said panel and releasing it, thereby causing the spring to jerk upon the cords and effect rapid movement of the figures.

50 2. A toy comprising a vertical panel, a plurality of figures in front of said panel, a plurality of cords on which said figures are hung, said cords extending to the rear of said panel and being slidably supported, a resilient plate behind said panel rigidly anchored at one end and having its opposite end portion free to move toward and from the panel, said cords being secured to said plate at points remote from its anchored end, and means for alternately springing said

plate toward the panel and releasing it, thereby causing the plate to jerk upon the cords and effect rapid movement of the figures.

3. A toy comprising a base, a plurality of figures over said base, means connected to and loosely supporting said figures in balanced positions, and means for actuating said supporting means to lower the figures slowly toward the base and rapidly raise them from the latter, said figures having supporting base-engaging feet disposed forwardly of the center of gravity and having upwardly and rearwardly inclined bottom portions upon which they tilt away from each other when said figures are lowered and said feet engaged with the base, whereby upon initial upward movement of said supporting means, said figures are caused to quickly tilt toward each other.

4. A structure as specified in claim 3; said supporting and actuating means including cords upon which said figures are hung, and a spring connected to said cords for jerking them to quickly move the figures upwardly.

5. A toy comprising a casing having a transparent front panel and another panel behind and parallel with said transparent panel, a resilient plate behind said other panel and anchored at its lower end, a pair of figures loosely received between the two panels, a pair of cords upon which said figures are loosely hung, said cords extending to the rear of said other panel, being slidably supported and being connected to the upper end of said resilient plate, and a crank shaft passing across the interior of the casing at the upper end of said resilient plate, said crank shaft being adapted to alternately spring said plate forwardly and release it.

6. A toy comprising a support, a plurality of figures adjacent said support, a plurality of cords slidably arranged upon the support and having one end attached to the figures, a spring mounted adjacent and having a portion movable toward and from the support, said cords having their other ends connected to said spring portion, and means for alternately forcing said spring portion toward said support and releasing it, thereby causing the spring to jerk upon the cords and effect movement of the figures.

In testimony whereof I have hereunto affixed my signature.

JOHN G. WILSON.
